(57) **CLAIM**

The ornamental design for a goal post display, as shown.

DESCRIPTION

FIG. 1 is a perspective view of the goal post display;
FIG. 2 is a left side elevational view of the goal post display;
FIG. 3 is a front elevational view of the goal post display;
FIG. 4 is a right side elevational view of the goal post display;
FIG. 5 is a rear elevational view of the goal post display;
FIG. 6 is a top plan view of the goal post display; and,
FIG. 7 is a bottom plan view of the goal post display.
In the drawings, the broken lines represent portions of the
goal post display that form no part of the claimed design.
